UNITED STATES PATENT OFFICE.

EDWIN F. HULBERT, OF MILWAUKEE, WISCONSIN, ASSIGNOR TO JIFFY DESSERT COMPANY, OF WAUKESHA, WISCONSIN, A CORPORATION OF WISCONSIN.

SEALED RECEPTACLE.

1,385,831.

Specification of Letters Patent. Patented July 26, 1921.

Application filed October 4, 1919. Serial No. 328,604.

To all whom it may concern:

Be it known that I, EDWIN F. HULBERT, a citizen of the United States, residing at Milwaukee, in the county of Milwaukee and 5 State of Wisconsin, have invented certain new and useful Improvements in Sealed Receptacles, of which the following is a specification, reference being had therein to the accompanying drawings, forming a part 10 thereof.

My invention relates to an improvement in paper receptacles and more especially those which are adapted to contain fine powdery materials, and the primary object 15 of the invention is to provide a receptacle composed of moisture proof paper and folded in such a manner as to bring all of the free edges either to the mouth thereof in lapped relation or close thereto and folded 20 in the ends thereof and sealed thereby, and to do the same with the use of a minimum amount of paper.

It is a further object of the invention to have a receptacle that may be easily made 25 by automatic machinery, may be made out of a square sheet of paper and one that provides a better closure because the cumbersome top folds previously in use are avoided. I am also enabled by my invention to form 30 a better closure and more completely lock all of the openings. I am further enabled to produce a bag which is smooth on both sides thereof, all the folds being on the ends thereof, thus giving me not only an article 35 of improved appearance but also a flat space available for decoration or the printing of either advertisements, directions, or such other matter as it may be desired to place thereon. A further improvement consists.

40 in making the bag with short folds of comparatively few sheets of material, so that the receptacle may be produced by machinery with a greatly increased rapidity over methods now in use and without the tearing 45 of the material when the same is ironed hard to complete the closures. Furthermore, the use of any paste, metallic fastening means, tongues, or punched fasteners in any part of the bag is avoided.

50 In the accompanying drawing Figure 1 shows a plan view of the sheet from which the receptacle is folded; Fig. 2 is a perspective view of the receptacle in which the primary folding has taken place; Fig. 3 is a

perspective view of the same in which the 55 secondary folding has taken place; Fig. 4 shows in perspective the receptacle completed except the closure; Fig. 5 shows in perspective the first fold of the closure; Fig. 6 the completed closure; and Fig. 7 an optional additional closing means by corrugation of the ends thereof.

In making the bag the blank of Fig. 1 is preferably a square of paraffin paper or so-called wax paper and it is folded to form 65 the bottom 1, smooth sides 2, end pieces 3, and wings 4. The end pieces 3 meet the sides 2, the wings 4 being folded outwardly therefrom in the edge 5. These wings 4 are then folded so as to lap over each other 70 and the ends 3 as shown in Fig. 3, and then after the bag has been filled with the material it is to carry the upper extension of the sides 2 or flaps 6 are brought together as shown in Fig. 4, the ends 3 and wings 4 are 75 then indented sharply as shown in Fig. 4 and the edges 5 and the topmost portion of the wings 4 are sharply ironed to form a sharp closure which will prevent the drawing up of the powdered contents. 80

The top seal is effected by bending the flaps 6 back upon the sides 2 in excess of 90 degrees as shown in Fig. 5 and then again bending both free portions of the flaps 6 so that the same lie flat upon the sides 2 of the 85 bag. These edges are ironed into this position by a stroke of the jaws of the machine and retain these positions substantially. If preferred they can be still further locked by corrugating the ends of the flaps 6 as 90 shown in Fig. 7 with the corrugations 7.

Having completely described my invention, I claim:

A smooth sided sealed receptacle formed from a single square sheet of material, the 95 bottom being laid out upon the diagonal thereof, all of the corners of the sheet being brought to points above the mouth of the receptacle, the receptacle being formed, closed, and sealed by then folding the free 100 edges into sharply acute angles and making sealing corners by the intimate contact thereof.

EDWIN F. HULBERT.
